UNITED STATES PATENT OFFICE.

THOMAS GRIFFITH, OF NEAR MANCHESTER, COUNTY OF LANCASTER,
ENGLAND.

STAIR-PAD.

SPECIFICATION forming part of Letters Patent No. 313,202, dated March 3, 1885.

Application filed April 24, 1884. (No model.) Patented in England August 1, 1883, No. 3,761.

To all whom it may concern:

Be it known that I, THOMAS GRIFFITH, a subject of the Queen of the United Kingdom of Great Britain and Ireland, residing at Ivy 5 Lea, High Lane Chorlton-eum-Hardy, near Manchester, in the county of Lancaster, England, manager, have invented certain new and useful Improvements in Stair-Pads, of which the following is a description, reference being 10 had to the accompanying drawings, in which—

Figure 1 is a perspective view of a pad for a separate stair or stair-tread constructed according to my invention. Fig. 2 is a perspective view of a continuous pad constructed according to my invention.

My invention relates to improvements in that form of stair-pads or coverings for the treads of stairs or landings or other similar purposes where a soft material—such as woolen 20 felt—is required to support a carpet or mat or other covering in order to render the tread quieter and cause the carpet or mat or other covering to wear a greater length of time.

In carrying out my invention, I take a felt 25 consisting of wool, hemp, jute, or other such material, of any thickness or consistency required, and cut it into certain lengths and widths, as may be necessary to suit the carpets, mats, or other coverings it may be intended 30 to support.

For a stairway pads may be made for the treads only, as shown in Fig. 1, or in a continuous length with the stair-carpet for covering treads and risers both on landings or other 35 places, as shown in Fig. 3, as may be required. I then form one or more rows of stitching, *a a*,

around or along the edges of such pads or pieces, as the case may be, either straight and parallel in a pattern or otherwise, such stitching being done either before or after the felt 40 is cut up.

Felt pads thus made will not stretch, nor will their edges become frayed, as would be the case were they not stitched. The stitching *a a* is all that is necessary to hold together 45 a pad of felt of the greatest thickness necessary, without any bag or external covering, such as is used to envelop or cover the fibrous material of which the bodies or substance of other stair-pads and carpet-linings is composed.

I am aware that stair-pads and carpet-linings have been composed of a layer or layers of felt covered on each side with paper or with woven fabric, and that the said layer or layers 55 and covering have been united by stitching or quilting through them at intervals all over; but such pads differ from my invention, in which there is only a single thickness of felt without covering, and stitched only at the 60 edges.

What I claim as my invention, and desire to secure by Letters Patent, is—

A stair-pad consisting of a single uncov- 65 ered thickness of felt stitched along the edges, substantially as herein described.

THOMAS GRIFFITH.
